[57] ABSTRACT

An auxiliary mechanism for operating a circuit breaker handle is provided with a lever carrying spaced straight rollers that engage a handle mounted straight roller positioned therebetween, with the axis of the handle roller being at right angles to the axes of the lever mounted rollers. The lever and handle pivot are in perpendicular planes, and the axis for the handle roller is at right angles to the plane of movement for the handle.

FIG. 6.

FORCE TRANSFER MEANS FOR OPERATION OF A CIRCUIT BREAKER INCLUDING ROLLERS ON AN AUXILIARY OPERATOR AND THE CIRCUIT BREAKER HANDLE

This invention relates to molded case circuit breakers in general and more particularly relates to a low friction auxiliary mechanism for operating the circuit breaker handle.

Auxiliary mechanisms for operating molded case circuit breakers are often provided with a fork-shaped lever that embraces an extension of the circuit breaker operating handle. The latter is pivoted in a plane perpendicular to the plane of movement for the lever so that considerable friction exists between the engaging parts, with the lever usually being constructed of metal and the circuit breaker handle being constructed of plastic.

This friction results from the continuously changing point of contact between the lever and the handle due to the changing point of intersection, causing the lever to slide up and down on the handle while being subject to considerable pressure. As the metal lever digs into the relatively soft plastic handle, a rough recess forms in the handle adding further to the friction resisting operation of the auxiliary mechanism.

The prior art has sought to overcome this problem by adding a barrel-shaped roller to each side of the fork-shaped lever. This was only partially successful in that the barrel shape of each roller was only a rough approach to the changing line of contact between lever and handle so that the rollers on the fork dug into the handle. It appears that a close-tolerance design for the exterior of the roller cannot be achieved economically because of the large number of components involved in a circuit breaker and an auxiliary handle mechanism therefor.

In accordance with the instant invention, the fork-shaped lever of the auxiliary mechanism is provided with spaced straight, rather than barrel-shaped, metal rollers that engage another straight metal roller on the circuit breaker handle. The fork and handle move in planes at right angles to one another, the rollers on the fork rotate on axes perpendicular to the plane of movement of the fork, and the roller on the handle rotates about an axis perpendicular to the plane of movement for the handle.

Since the ratio of roller outside diameter to roller shaft diameter is large and each roller is free to rotate, only rolling friction will exist at the point of contact between rollers. The only sliding friction will occur at the relatively small diameter roller shafts where friction force moments will be very low because of small radii. "Digging" into the handle will not occur so that force requirements at the operating handle will remain constant for a reasonable number of operations.

Accordingly, a primary object of the instant invention is to provide a novel engaging means at the point of intersection between a circuit breaker handle and an auxiliary mechanism for operating the handle.

Another object is to provide engaging means of this type that is economical to construct.

Still another object is to provide engaging means of this type so constructed that friction forces are substantially eliminated.

A further object is to provide engaging means of this type so constructed that handle force requirements will

remain constant after many operations of the handle.

These objects as well as other objects of this invention will become readily apparent after reading the following description of the accompanying drawings in which:

FIG. 1 is a plan view of a circuit breaker constructed in accordance with teachings of the instant invention.

FIG. 2 is a longitudinal cross-section taken through line 2-2 of FIG. 1, looking in the direction of arrows 2-2, and including an auxiliary handle operating mechanism not shown in FIG. 1.

FIG. 3 is an exploded perspective of one overcenter toggle mechanism and selected elements connected thereto.

FIG. 4 is an exploded perspective of the movable contact structure for one phase.

FIG. 5 is an enlarged longitudinal cross-section of the auxiliary handle operating mechanism taken at right angles to the section of FIG. 2.

FIG. 6 is a cross-section taken through line 6-6 of FIG. 5 looking in the direction of arrows 6-6.

Now referring to the figures. Three phase molded case circuit breaker 25 of FIGS. 1 and 2 includes an individual overcenter spring-powered toggle operating mechanism. Prior art examples of circuit breakers having more than a single operating mechanism for all phases are disclosed in U.S. Pat. Nos. 2,067,935 and 3,125,653.

Circuit breaker 25 includes a molded housing constructed of base 26 and removable cover 27 joined along line 28, and provided with longitudinal internal partitions 31, 32 which divide housing 26, 27 into three longitudinally extending compartments, one for each phase of circuit breaker 25. Cover 27 is provided with aperture 29 through which stubby bifurcated extension 33 of operating handle means 30 extends. Each section 35 of handle extension 33 receives an individual pin 34 extending upwardly from the web portion of inverted generally U-shaped operating yoke member 35 of the center phase. Operating members 35 of the outer phases are each secured to handle means 30 by a pair of screws 152.

Member 35 is pivoted to the spaced arms of generally U-shaped operating mechanism frame 36 at outwardly extending lugs 37. Bolts 48, received by threaded apertures of turned edges 36a at the bottom of frame 36, fixedly secure the latter to base 26. Transverse tie member 49 is riveted to the arms of frame 36 to maintain spacing therebetween and to stabilize the frame structure.

Four-tensioned coil springs 38, each connected at one end thereof to the web of operating member 35, combine to constitute the main operating spring means for the overcenter toggle-type contact operating mechanism. The other ends of springs 38 are connected to spaced plates 39, 39 that are pivotally mounted to toggle knee pin 41 connecting upper 42 and lower 43 toggle links. The upper ends of upper toggle links 42 are pivotally connected to the spaced arms of latchable cradle 40 at pins 44, and the lower ends of lower toggle links 43 are pivotally connected to contact carrier 45 by rod 46 that extends between the spaced arms of contact carrier 45. The spaced arms of cradle 40 are positioned adjacent the inner surfaces of the spaced

arms of frame 36 and are pivotally connected thereto by pins 47 that are secured to frame 36.

Under normal operating conditions plate 51, secured to web 40a of cradle 40, is in engagement with forward latching surface 52 of auxiliary latch 53. The latter is loosely mounted to pivot rod 55 extending between the spaced arm of mechanism frame 36 and slightly outboard thereof. The coiled end sections of torsion spring member 56 are wound about pivot rod 55, with the ends of these sections bearing against rod 57 and auxiliary latch 53 to bias the latter counterclockwise against stop rod 58. The ends of rods 57 and 58 are supported by the arms of frame 36. Leaf spring 73 secured to auxiliary latch 53 bears against pivot rod 55 biasing latch 53, so that rod 55 will normally lie at the central portion of V-shaped notch 74 of primary latch 53.

The ends of rod 55 projecting outboard of mechanism frame 36 are engaged by the hooked portions at the forward extensions 59 of the arms for U-shaped trip unit frame 60, whose web portion is seated on a forward surface of load strap 61, being secured thereto by bolts 62 that extend through clearance apertures in strap 61 and are received by threaded inserts molded in base 26.

Rear latch tip 54 engages latch tip 63 at the U-shaped forward arm of primary latch 65, whose rear latch tip 64 is engaged by latch plate 67 mounted on one leg of L-shaped carrier 66. Primary latch 65 is pivotally mounted to trip unit frame 60 at stub shaft 69, and the carrier is pivoted on rod 68 to frame 60. Tension spring 75 biases primary latch 65 in a clockwise direction about pivot 69. The other leg of carrier 66 is provided with transversely extending pin 71 that projects into triangular window 72 of primary latch 65 at a portion thereof near rear latch tip 64, for a reason to be herein-after explained. Tension spring 76, connected between frame 60 and carrier extension 66a, biases carrier 66 in a counterclockwise direction about its pivot 68 toward latching position.

When automatic tripping occurs, carrier 66 in the faulted phase is moved clockwise either by the deflection of bimetal 77 or movement of magnetic armature 78, causing latch plate 67 to release primary latch 65, which in turn releases secondary latch 53 and permits main operating springs 38 to rotate cradle 40 in a counterclockwise direction to break toggle 42, 43. The force from main spring 38 acts through cradle 40, primary latch 53, and secondary latch 65 to drive cam surface 78, bounding opening 72, against extension 71 to rotate carrier 66 clockwise, with surface 79 thereof engaging ear 81 of extension 82 on tripper bar 80 which extends between all three phases. This causes tripper bar 80 to rotate in a counterclockwise direction, so that extensions 82 in the non-faulted phases rotate counterclockwise with cam surfaces 83 thereof engaging transversely extending pin 84 of carriers 66 in the non-faulted phases, rotating them clockwise or in the tripping direction, to release the cradle latching systems in the non-faulted phases, so that the contacts of all three phases are open.

In order to prevent closing of the contacts of any one phase before the operating mechanisms of all phases are latched, circuit breaker 25 is provided with a defeater latching system including defeater latch 80' and defeater lever 90. Latch 80' is pivotally mounted upon rod 55 and includes protrusion 81' extending over the rear of cradle 40 when the latter is in latched position.

Latch 80' further includes protrusion 82' extending over the forward end of defeater lever 90 in slot 91 thereof. Coiled tension spring 83' is connected between stop rod 57 and latch 80', passing partially around rod 55, to bias latch 80' in a counterclockwise direction about its pivot 55 and maintaining this pivot in the basic position at the right end of slot 84' in latch 80'. This basic position is established through the engagement of latch stop surface 86 and stop rod 57.

Slot 91 is in the web of the U-shaped forward portion of latch lever 90, with the U arms having pivot pin 69 for lever 90 extending therethrough. Rear portion 89 of lever 90 is positioned below and in interfering relationship with transverse pin 71 mounted to latch plate carrier 66.

During normal relatching of circuit breaker 25, inwardly protruding portions of the operating member 35 arms engage outboard portions of pin 44 to pivot cradle 40 clockwise, whereby the latter cams defeater latch 80' away and moves below auxiliary latch 53. Upon release of the circuit breaker operating handle 30, the elements of the latch train 53, 65, 66 move into place. However, should any of these elements fail to properly engage or should cradle 40 not have been moved far enough to engage auxiliary latch 53, cradle 40 will pick up defeater latch protrusion 81', causing clockwise rotation of defeater latch 80'. In turn, this causes defeater latch protrusion 82' to engage defeater lever 90 and rotate the latter counterclockwise with the rear end 89 thereof contacting carrier extension 71 so that latch plate carrier 66 is pivoted in a clockwise or latch train releasing direction. During this releasing movement of carrier 66, surface 79 thereof engages nose 81 of one trip bar extension 82 to rotate common tripper bar 80 in a counterclockwise direction, with the other extensions 82 on bar 80 engaging pins 84 on the latch plate carriers 66 of the other poles, thereby causing the latch systems of all other poles to be released.

The lower end of bimetal 77 is fixedly secured to shading coil 99, and these elements are fixedly secured to molded frame member 95 secured to trip unit frame 60. The horizontal leg of inverted U-shaped stationary magnetic frame member 98 passes through the center of coil 99. Member 98 is secured to the rear of frame 60, with the vertical legs of member 98 being on opposite sides of load strap 61. The other U-shaped magnetic frame member 96 is secured directly to load strap 61, with the ends of the arms for frame members 96 and 98 confronting one another in spaced relationship. Thus, current flowing in load strap 61 generates flux in magnetic frame 96, 98 which induces current flow in shading coil 99 and thereby generates heat that is conducted to bimetal 77 for heating thereof. Coiled tension spring 97, connected between armature 78 and an element mounted to the rear transverse part 60 of frame 60, biases the former away from two spaced legs 98a extending upward from the horizontal leg of member 98, and is drawn downward toward legs 98a when overload currents generate sufficient magnetic flux in magnetic frame 78, 96, 98.

With particular reference to FIG. 4, it is seen that the movable contact structure for each phase of circuit breaker 25 includes eight main contacts 103-110 and a single arcing contact 101. The latter contact 101 is mounted at the forward end of arm 112, which is pivotally mounted to carrier 45 at toggle connecting rod 46. Main contacts 103-110 are arranged in two parallel

rows positioned to the rear of arcing contact 101 and disposed at right angles to the plane of movement of arcing contact arm 112.

Main contacts 103-106 in the forward row are mounted to individual contact arms 113-116 respectively, all pivotally mounted to carrier 45 on rod 46. Main contacts 107-110 in the rear row are mounted to the forward end of the respective contact arms 117-120, respectively, pivotally mounted to carrier 45 on rod 102. All of the contact arms 112-120 are connected to load strap 61 by means of individual stacks 121 of flexible sheet conductors. Contact arms 113-116 are in alignment with and extend over the respective contact arms 117-120, so that the latter group of arms 117-120 block downward movement of the former group of arms 113-116 to establish the open circuit position of contacts 103-106 in a manner which will hereinafter be seen. The open circuit position for arcing contact arm 112 is established through engagement thereof with aligned pins 123, 124 which mount the respective pairs of main contacts 117, 118 and 119, 120 to auxiliary carriers 125, 126 respectively. Notch 122 along the lower edge of arcing contact arm 112 provides clearance for pins 123, 124.

Auxiliary carrier 125 is an inverted U-shaped member whose arms extend downwardly through cutouts 131, 132 in the web portion of contact carrier 45 and straddle four contact arms 113, 114, 117, 118. Pin 123 secures contacts 117, 118 to the lower ends of the arms comprising auxiliary carrier 125. The web of auxiliary carrier 125 is biased towards the web of contact carrier 45 by coiled compression spring 127, which is wound around the threaded body of bolt 128 whose head is positioned below the web portions of contact carrier 45. Self-locking nut 133 mounted to bolt 128 is rotated to adjust the loading of spring 127, with the rectangular shoulder of bolt 128 cooperating with rectangular cutout in carrier 45 to prevent rotation of bolt 128. Thus, in the open circuit position, spring 127 biases the web of auxiliary contact carrier 125 against the web of contact carrier 45, and when the contacts are closed there is a space between the webs of these contact carriers 45, 125, so that the force exerted by spring 127 acts to bias contacts 107, 108 into firm electrical engagement with their respective cooperating contact portions on line strap 136.

The mounting of contact arms 119, 120 to auxiliary contact carrier 126 and mounting of the latter to contact carrier 45 is the same as the mounting of contact arms 117, 118 and auxiliary carrier 125, so that this description will not be repeated.

Biassing forces for each of the contacts 103-106 in the forward row are provided by individual coiled compression springs 138, and each of these springs is mounted in the same way so that only the mounting of one of these springs will be described. The lower end of spring 138 extends into depression 139 in the upper surface of main contact arm 113, and the rear of spring 138 extends into tubular support 141 through the open bottom thereof. Support 141 is mounted to the upper surface of carrier 45 at the web portion thereof, and its upper end is threaded to receive adjusting screw 142 whose lower end bears against disc 143 abutting the upper end of spring 138. If screw 142 is adjusted to set the contact pressure exerted by spring 138, lock nut 144 is tightened to lock this adjustment.

In order to increase the area of engagement between main contacts 103-110 and their respective cooperating stationary main contacts in the very limited space available, it is noted that each of the main contacts is provided with a portion extending outward of its respective contact arm. That is, in order to utilize the space below arcing contact 112, main contacts 104, 105, 108, 109 have been extended beyond their respective contact arms 114, 115, 118, 119 to project below arcing contact arm 112. Similarly, main contacts 103, 106, 107, 110 have been extended outboard from their respective contact arms 113, 116, 117, 120, to lie in the space below the outboard arms of auxiliary contact carrier 125, 126 and other elements used to connect the movable contact structure to the contact operating mechanism.

The forward end of arcing contact arm 112 is biased downward away from the web portion of contact carrier 45 by coiled compression spring 171 whose lower end is positioned by pin 172 extending upward from arm 112. The upper end of spring 171 extends into tubular member 173, on the upper surface of the carrier 45 web portion, through the bottom of member 173 and abuts the closed upper end thereof.

The spaced arms of contact carrier 45 are provided with rearward extensions 45a, 45b that are spaced by and secured to shouldered cylindrical tube 146. After all contact structures, operating mechanisms, latching devices, and automatic trip units are mounted to base 26, and all adjustments to these mechanisms have been made, the contact structures of all phases are operated to the closed circuit position, so that the tubular members 146 of all phases are axially aligned and are positioned above barriers 31, 32 and the longitudinal sides of base 26. Thereafter, cylindrical tie bar 147 is driven longitudinally in the members 146 of all phases to constitute a rigid mechanical connection between the movable contact structures of all phases. The fit between tie rod 147 and tubular members 146 is tight enough to prevent unintentional axial movement of tie rod 147, yet permits tie rod 147 to be removed for convenient servicing and replacement of parts. Mechanism frame 36 is provided with aligned elongated slots 148 to provide clearances for movement of rod 147 during opening and closing of the movable contact structures.

Auxiliary handle operating mechanism (FIGS. 2, 5 and 6) is mounted directly to the front of cover 27 by four screws 251 located at opposite corners of shallow rectangular molded housing 252. Molded main operating handle 253 is positioned outside of housing 252 and is keyed to stub shaft 254 so as to be pivotable in a plane parallel to the front of housing 252. Shaft 254 is journaled by circular apertures in closely spaced parallel support plates 257 and 258. Plates 257 and 258 are secured together as part of an assembly which, for the most part, is disposed within housing 252 and is secured thereto by four bolts 259.

Parallel closely spaced plate-like sections 256a, 256b forming drive link 256 are joined at their left ends (with respect to FIGS. 5 and 6) at connecting part 256c, and at this region drive link 256 is keyed to shaft 254. Main link 260 is freely mounted at its right end (with respect to FIGS. 5 and 6) on stub shaft 261 whose ends are held in circular apertures of support plates 257, 258. Links 256, 260 extend toward one another and are provided at their respective free ends with longitudinally extending slots 263, 264 which receive roller portions of con-

necting means 265. Other roller portions of connecting means 265 act as followers, being disposed in aligned cam slots 266 in support plates 257, 258.

The central portion of main link 260 is provided with cutout 267 wherein spaced rollers 268, 269 are disposed. Stub shafts 271, 272, whereon the respective rollers 268, 269 are freely mounted, are disposed within circular apertures of retainer plates 273 secured on opposite surfaces of main link 260 by four rivets 274. Roller 222, mounted on extension 33 of circuit breaker handle 30, is disposed between rollers 268, 269 so as to be engageable thereby for transfer of motion from main operating handle 253 to circuit breaker handle 30.

Thus, it is seen that a force supplied to pivot arm 253 is applied directly to drive link 256 which acts through connecting means 265 to pivot main link 260. This motion of link 260 causes the arcuate surface of one or the other of rollers 268, 269 to engage the arcuate surface of roller 222 on circuit breaker handle extension 33 to thereby pivot circuit breaker handle 30 for opening and closing of circuit breaker 25 depending upon the direction of movement of main operating handle 253.

It is noted that cam slots 266 force pin-roller connecting means 265 to travel along a predetermined path, and in this manner the effective relative lengths of links 256, 260 are varied in accordance with the position of handle 253. The effective lengths of links 256, 260 are the distances between the connecting means 265 and the respective fixed pivots 254, 261. In the embodiment illustrated, cam slot 266 is an arc drawn about a center located to the left of fixed pivot 254 as seen in FIGS. 5 and 6. The shape of cam slot 266 and its location with respect to fixed pivots 254, 261 are chosen so that the mechanical advantage afforded by main operating handle 256 and link system 256, 260 varies in accordance with the force required to operate the contact operating mechanism.

The force that must be applied to handle 253 is also minimized by having the driving connection between auxiliary mechanism 250 and circuit breaker operating handle 30 take place between roller 222 and rollers 268, 269, all of which are freely rotatable. This essentially eliminates frictional engagement. This arrangement also permits rollers 222, 268, 269 to be of substantially uniform diameters throughout the lengths thereof.

It is noted that because of high magnitude current flow in circuit breaker 25, the magnetic fields generated are very strong. In order to reduce adverse effects of these magnetic fields, many of the frame parts and operating mechanism parts are constructed of non-magnetic stainless steel.

For those features of construction in circuit breaker 25 that have not been described in detail herein, reference is made to one or more of the copending applications Ser. Nos. 275,568, 275,577, 275,446, 275,578,

275,454, 275,508, 275,621, 275,623, 275,624, 275,569, 275,522, 275,521, 275,523, and 275,622, all filed of even date herewith, and all assigned to the assignee of the instant invention.

5 Although there has been described a preferred embodiment of this novel invention, many variations and modifications will now become apparent to those skilled in the art. Therefore, this invention is to be limited not by the specific disclosure herein but only by the appending claims.

10 The embodiments of the invention in which an exclusive privilege or property is claimed are defined as follows:

15 1. The combination comprising a circuit breaker and an auxiliary handle mechanism mounted thereto; said circuit breaker including an enclosure having a front wall, and a spring powered overcenter toggle contact operating mechanism including a contact operating handle having an extension projecting through an opening in said front wall and mounted for pivotal movement in a first plane; said auxiliary handle mechanism including support means, a main operating handle mounted in front of said support means, a lever pivotally mounted to said support means and operatively connected to said main operating handle means to be operated thereby in a second plane at right angles to said first plane; said lever having spaced formations between which said extension of said contact operating handle is disposed; a first roller mounted on said extension to rotate freely on an axis perpendicular to said first plane; said spaced formations including second and third rollers laterally spaced and disposed with the axis of said first roller passing therebetween; said second and third rollers being engageable with said first roller to transmit motion of said lever to said contact operating handle; said second and third rollers being mounted on said lever to rotate freely on axes generally perpendicular to said second plane.

20 2. A combination as set forth in claim 1 in which the opening in said front wall and mounted for pivotal movement in a first plane; said auxiliary handle mechanism including support means, a main operating handle mounted in front of said support means, a lever pivotally mounted to said support means and operatively connected to said main operating handle means to be operated thereby in a second plane at right angles to said first plane; said lever having spaced formations between which said extension of said contact operating handle is disposed; a first roller mounted on said extension to rotate freely on an axis perpendicular to said first plane; said spaced formations including second and third rollers laterally spaced and disposed with the axis of said first roller passing therebetween; said second and third rollers being engageable with said first roller to transmit motion of said lever to said contact operating handle; said second and third rollers being mounted on said lever to rotate freely on axes generally perpendicular to said second plane.

25 3. A combination as set forth in claim 1 in which the extension of the contact operating handle is constructed of insulating material; said first, second and third rollers being constructed of material generally having the wear-resistant properties of a hardened steel.

30 4. A combination as set forth in claim 3 in which said extension of the contact operating handle is constructed of insulating material; said first, second and third rollers being constructed of material generally having the wear-resistant properties of a hardened steel.

35 5. A combination as set forth in claim 4 in which the extension of the contact operating handle is constructed of insulating material; said first, second and third rollers being constructed of material generally having the wear-resistant properties of a hardened steel.
